(57) **CLAIM**

The ornamental design for a shoe sanitizer, as shown and described.

DESCRIPTION

FIG. 1 is an isometric view of a shoe sanitizer showing our new design.

FIG. 2 is an isometric view showing a second positional variation thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken line showing is included for illustrative purposes only and forms no part of the claimed design.

1 Claim, 5 Drawing Sheets
